UNITED STATES PATENT OFFICE.

OLIVER B. JACOBS, OF EAST ORANGE, NEW JERSEY, ASSIGNOR TO AMERICAN TELEPHONE AND TELEGRAPH COMPANY, A CORPORATION OF NEW YORK.

REPEATER CIRCUITS.

Application filed May 17, 1919. Serial No. 297,866.

To all whom it may concern:

Be it known that I, OLIVER B. JACOBS, residing at East Orange, in the county of Essex and State of New Jersey, have invented certain Improvements in Repeater Circuits, of which the following is a specification.

This invention relates to transmission circuits and more particularly to transmission circuits in which repeaters are employed.

One of the objects of this invention is to simplify the apparatus and reduce the expense connected with the installation of repeater equipment for telephone lines. Another object of the invention has reference to the provision of means whereby one repeater may be employed for a plurality of connecting circuits. Other and further objects of the invention will more fully appear in connection with the detailed description hereinafter given.

Where cord circuit repeaters are employed in the establishment of connections between long distance transmission lines, it is customary to provide a repeater unit for each repeater cord at each position. Under certain circumstances, however, it is desirable that the same repeater unit be used for repeater cords at two positions so that the amount of apparatus necessary may be reduced. The repeater unit comprising the amplifiers, relays, coils, etc., is usually arranged at a point somewhat distant from the switchboard and is connected with the switching cords and controlling keys such as the listening, splitting and repeater control keys by means of a series of conductors extending from the repeater unit to the switchboard position. In accordance with the present invention the apparatus is so arranged that the conductors leading from the repeater unit may be switched into connection with conductors leading to either of two switchboard positions. Means are provided whereby when the operator at one position utilizes a repeater cord at that position in establishing a connection, the conductors leading from the repeater unit are switched into connection with the switching plugs and controlling keys of that cord so that the repeater is rendered independent of the switching plugs and controlling keys of the corresponding cord at the other position. At the same time a busy lamp is

caused to glow at the other switchboard position to indicate to the operator that the repeater is already in use.

The invention may now be more fully understood by reference to the following description when read in connection with the accompanying drawings, Figs. 1 and 2 of which when taken together constitute a circuit diagram of one embodiment of the invention.

Referring to the drawings the usual two-way two repeater circuit including vacuum tube amplifiers A and A' is shown in Fig. 2. Line conductors L and artificial line conductors N are associated with the one end of the repeater and line conductors L' and artificial line conductors N' are associated with the other end of the repeater. The conductors L and N are normally connected over conductors L₁ and N₁ to a twin plug P₁ at one operator's position X and the conductors L' and N' are similarly normally connected over conductors L₂ and N₂ to the outgoing plug P₂ at said position. These twin plugs are so arranged that upon being inserted in corresponding twin jacks real transmission lines are connected with the line conductors L₁ and L₂ respectively and artificial lines suitable for balancing the transmission lines are connected to the conductors N₁ and N₂ respectively. In the idle condition of the circuit the repeater is disconnected from the line conductors L and L', the conductors L being connected to cord conductors C which normally extend over cord conductors C₁ over the contacts of the splitting key K₂ and over cord conductors C₂ which are normally connected to cord conductors C' normally associated with line conductors L' of the repeater circuit. A listening key K₁ is provided whereby the operator's set may be bridged across the toll cord circuit formed by the conductors C, C₁, C₂ and C'. A repeater control key K₃ is also provided for controlling the operation of the repeater.

The circuits associated with the plugs P₁ and P₂ and the keys K₁, K₂ and K₃ normally extend over the contacts of a series of switching relays 1, 2, 3, 4 and 5. When these switching relays are energized, these connections are opened and the various circuits leading from the repeater unit of Fig. 2 are associated by means of alternative connections with a similar repeater cord lo-

cated at a second operator's position designated in the drawing as Y. The cord circuit at position Y terminates in twin plugs P_1' and P_2' and is provided with a listening key K_1' , splitting key K_2' and repeater control key K_3' . The transmission conductors L, N, C, L', C' and N' of the repeater unit of Fig. 2 may be connected over alternative contacts of the switching relays 1 to 5, inclusive, and over alternative transmission connections L_1' , N_1' , C_1' , L_2' , N_2' and C_2' to the switching plugs and controlling keys of the cord circuit at position Y. The various circuit controlling conductors leading from the repeater unit to the switchboard positions may also be switched by means of the relays 1 to 5 inclusive.

The circuits of the switching relays are so arranged that if the operator at position X inserts either or both of the plugs P_1 and P_2 into corresponding jacks, relays 1 to 5 will be removed from the control of the operator at position Y and the various conductors leading from the repeater unit will remain connected over the back contacts of the switching relays to the apparatus of the cord at position X. Busy lamps 6 and 7 are provided at positions X and Y respectively and upon the establishment of the circuit condition above referred to, busy lamp 7 at position Y is caused to glow to indicate to the operator at that position that the repeater is in use in connection with the cord at position X. If the operator at position Y should first obtain control of the circuit by inserting either or both of the plugs P_1' , P_2' in corresponding twin jacks, the switching relays 1 to 5, inclusive, will be actuated to switch the connection from the repeater unit of Fig. 2 to the cord circuit apparatus at position Y thereby removing the repeater from the control of the operator at position X. At the same time the busy lamp 6 at position X is caused to glow to indicate to the operator at that position that the repeater is in use.

Further details of the apparatus may be best understood from a detailed description of the operation which is as follows:

Assuming that the operator at position X desires to establish a connection between an incoming transmission line and an outgoing transmission line through the repeater shown in Fig. 2. The operator will insert the twin plug P_1 in the twin jack of the incoming line thereby connecting the incoming line to conductors L_1 and the corresponding artificial line to conductors N_1 . A circuit is now completed from the grounded sleeve contacts of the twin jack over the sleeve contacts of the plug P_1 through the winding of relay 8 over the left hand contact of relay 10 and left hand back contact of relay 11 to battery. Relay 8 at its right hand contact disconnects the battery which

is normally connected over the right hand back contacts of relays 8 and 9 to the windings of relays 10 and 11 so that relays 10 and 11 will not operate in case the operator at position Y should insert either or both of the plugs P_1' and P_2' into line jacks. At its front right hand contact relay 8 connects battery to the busy lamp 7 at position Y thereby causing the lamp to glow to indicate to the operator at position Y that the repeater is engaged.

At its left hand front contact relay 8 connects ground through the resistance 12 and through the winding of relay 13 to battery. Relay 13 upon being energized completes a circuit from ground over its lower front contact over conductors 14 and 15 over the back contacts of ringing responsive relays 16 and 17 and over conductor 18 through the winding of slow release relay 19 to battery. Relay 19 upon being energized opens the circuit which would otherwise have been completed for relay 20 from ground over the lower front contact of relay 13 over the back contact of relay 19 and through the winding of said relay 20 to battery.

A transmission circuit now extends from the incoming line over the left hand tip and ring contacts of the plug P_1 , line conductors L_1 , left hand back contacts of switching relay 2, line conductors L, back contacts of relay 21 over conductors C, right hand back contacts of switching relay 3 over conductors C_1 over the right hand normal contacts of splitting key K_2 over conductors 22, left hand normal contacts of splitting key K_2 , conductors C_2 , left hand back contacts of switching relay 3, conductors C', back contacts of relay 23, conductors L' , back right hand contacts of switching relay 4 and over conductors L_2 to the right hand tip and ring contacts of the plug P_2 . The operator by throwing the listening key K_1 may bridge her set across the transmission circuit above traced at points 24 and 25.

In order to complete the connection, the operator now inserts the plug P_2 in the jack of the outgoing line and actuates the repeater control key K_3 , the listening key K_1 having in the meantime been restored. The insertion of the plug P_2 in the jack completes a circuit from the grounded sleeve contacts of the jack over the sleeve of the plug P_2 through the winding of relay 9 and over the back left hand contact of relays 10 and 11 to battery. Relay 9 at its right hand contact opens the circuit of relay 10 and 11 at another point to further prevent the actuation of these relays. At its left hand front contact relay 9 connects ground through the resistance 26 and through the winding of relay 27 to battery. Relay 27 upon being energized at its lower contact connects ground to point 28 but no circuit changes are produced as a result of

this connection since ground is already connected to said point over the lower front contact of relay 13.

- Upon actuating the repeater control key 5 K_3 a circuit is completed for the filament control relay 29 from battery through the winding of said relay over conductors 30 and 31 over the right hand make contacts of key K_3 over conductor 32, inner back 10 contact of relay 5 and over conductors 33 and 14 to point 28 and thence in parallel over the lower front contacts of relays 13 and 27 to ground. Relay 29 upon being energized connects the filaments of the amplifiers A and A' in series with the filament battery B' thereby rendering the amplifiers operative.

- The actuation of repeater control key K_3 also completes a circuit from the lower 20 grounded contacts of relays 13 and 27 to point 28 over conductor 34, left hand contact of relay 1, conductor 35, conductor 36, lower normal left hand and right hand contacts of splitting key K_2 , right hand normal 25 contact of listening key K_1 over conductor 37, inner right hand back contact of relay 1, conductor 38, upper front contacts of relays 13 and 27, conductors 39 and 40, left hand make contact of repeater control key 30 K_3 , conductor 41, left hand back contact of relay 5, conductors 42 and 43 through the winding of relay 44, back contact of relay 45, conductor 46 and thence in parallel 35 through the windings of relays 21 and 23 to battery. Relay 44 upon being energized opens the short circuits which are normally closed about the primary windings of the input transformers 47 and 48 of amplifiers A and A' respectively and connects said 40 input transformers to the input bridges 49 and 50 of the repeater. Relays 21 and 23 disconnect the line conductors L and L' of the repeater from the cord conductors C and C' and connect said line conductors through 45 windings of transformers 51 and 52 to the artificial line conductors N and N' respectively.

- The two-way repeater comprising amplifiers A and A' is now operative and is interconnected between the incoming and outgoing transmission lines through the connections to plugs P_1 and P_2 . Transmission from the incoming line passes over conductors L_1 , left hand back contacts of relay 2, 50 conductors L, front contacts of relay 21 over input bridge 49 through the input transformer 47 to the amplifier A which amplifies the transmitted variations and transmits them from the output circuit 53 and 55 through the transformer 52 where the energy divides, one-half being transmitted over the front contacts of relay 23 over conductors L', right hand contacts of relay 4 and conductors L_2 to the outgoing line and the other 60 half being transmitted over conductors N',

left hand back contacts of relay 4 and conductors N_2 to the artificial line. In a similar manner transmission from the outgoing line comes in over conductors L_2 over the right hand back contacts of relay 4, conductors 70 L', front contacts of relay 23, input bridge 50 and through the transformer 48 to the amplifier A'. The amplified variations are then transmitted from the output circuit 54 through the transformer 51, one-half of the 75 energy being transmitted to the incoming line over the front contacts of relay 21 and conductors L, left hand back contacts of relay 2, and conductors L_1 and the other half being transmitted over conductors N, 80 right hand back contacts of relay 2 and conductors N_1 to the artificial line.

If, with the circuits in the condition just described, ringing currents should be transmitted over the incoming line, said ringing current would flow over conductors L_1 and L to the ringing responsive relay 17. Said relay upon being energized by the ringing current opens the circuit previously traced for the slow releasing relay 19 which, upon 90 permitting its armature to retract, completes a circuit from ground over the front contacts of relays 13 and 27 to point 28 and thence over the back contact of relay 19 and through the winding of relay 20 to battery. 95 Relay 20 at its right hand front contact completes a circuit from ground over the lower front contacts of relays 13 and 27 to point 28, over conductor 34, left hand back contact of relay 1, conductors 35 and 36, lower normal contacts of splitting key K_2 , right hand normal contact of listening key K_1 , conductor 37, inner right hand back contact of relay 1, conductor 38, upper front contacts of relays 13 and 27, conductors 39 and 40, left 100 hand make contacts of repeater control key K_3 , conductor 41, left hand back contact of relay 5, conductors 42 and 55, right hand contact of relay 20 and through the winding of relay 45 to battery. Relay 45 is now 105 energized and opens the circuit previously traced through relays 44, 21 and 23. Relay 44 is accordingly deenergized and short circuits the input windings of the amplifiers A and A' to prevent ringing current from actuating the repeater. A holding circuit is 110 established for relays 21 and 23, however, from ground over the front contact of relay 45 over conductor 46 and through the windings of relays 21 and 23 in parallel to battery.

Returning to relay 20 a circuit is completed over the left hand front contact of said relay from ground over the lower front contacts of relays 13 and 27 to point 28 over the left hand front contact of relay 20 and through the winding of relay 56 to battery. Relay 56 upon being energized establishes a locking circuit from battery through its winding and over its upper front contact, 115 120 125 130

- over conductors 57 and 58, left hand normal contact of listening key K_1 , conductors 59 and 35 over the left hand back contact of relay 1 and conductor 34 to point 28 and thence to ground over the front contacts of relays 13 and 27. Relay 56 at its lower front contact completes a circuit from ground over conductor 60, right hand back contact of relay 1 and through the lamp 61 to battery.
- 10 The lamp 61 is now caused to glow thereby indicating to the operator that a call has come in over one of the lines interconnected through the repeater.
- The operator upon observing the glowing of the lamp 61 will throw the listening key K_1 to bridge her set across the cord. The actuation of the listening key opens the left hand contact of said key thereby opening the locking circuits above traced for the relay 56. Relay 56 is accordingly deenergized and the lamp 61 effaced. The right hand contact of the listening key K_1 is also opened thereby opening the circuit previously traced for the relay 45 which is deenergized and again connects relay 44 in circuit with relays 21 and 23. The original circuit for relays 44, 21 and 23 it will be remembered passes over the right hand contact of the listening key. As this contact is now open, relays 21 and 23 are deenergized in addition to the relay 44 which had already been deenergized. The deenergization of relays 21 and 23 results in the disconnection of the line conductors L and L' from the repeater and consequently the lines are associated through the cord connection, including conductors C , C_1 , the splitting key, conductors C_2 and C_3 .
- The operator having ascertained that the call came in over the line connected with the plug P_1 may, if she desires, disconnect the outgoing line by throwing the splitting key K_2 to the left so that she may communicate over the incoming line to the exclusion of the outgoing line. Should ringing current be transmitted from the outgoing line with the circuit in this condition the ringing current would flow over conductors L_2 , right hand back contacts of relay 4 and conductors L' to the winding of the ringing responsive relay 16. Relay 16 in responding to the ringing current opens a circuit previously traced for the relay 19 (which circuit was restored as soon as the ringing current which actuated relay 17 ceased) so that said relay 19 is again deenergized and causes the energization of relay 20. Relay 20 upon being energized does not complete a circuit over its right hand front contact for the relay 45 since the circuit of the relay 45 passes over the right hand contact of the listening key which contact is now open. Relay 20, however, completes the circuit of relay 56 at its left hand front contact and a locking circuit for the relay 56 is now established over the upper front contact of said relay over conductors 57, 58 and 62, lower left hand make contact of splitting key K_2 , lower right hand normal contact of splitting key K_2 over conductors 36 and 35, left hand back contact of relay 1 over conductor 34 to point 28 and thence to ground over the lower front contacts of relays 13 and 27. Relay 56 also completes the circuit of the lamp 61 which again glows.
- It will be noted that the locking circuit above traced for the relay 56 is now under the control of the splitting key instead of the listening key. Accordingly, the operator upon observing the glowing of the lamp, realizes that a ringing call has been transmitted from the outgoing line since she is already in communication with the incoming line. By throwing the splitting key to the right, she may place herself in communication with the outgoing line to the exclusion of the incoming line at the same time opening the locking circuit for relay 56 which is accordingly deenergized and effaces the lamp 61.
- Upon restoring the listening key and splitting key to their normal condition the circuit previously traced for relays 44, 21 and 23 will be again completed and the lines will be once more interconnected through the repeater. Upon withdrawing the plugs P_1 and P_2 from the jacks, the relays 8 and 9 will be deenergized thereby effacing the lamp 7 and opening the circuits of relays 13 and 27. The repeater control key K_3 will also be restored when the plugs are withdrawn from the jacks. The deenergization of relays 13 and 27 removes the ground connection from point 28 so that relays 19, 29, 21, 23 and 44, the circuits of which it will be remembered depended upon the ground connection to point 28, will be deenergized.
- It will be noted that in the connection heretofore described as having been set up by the operator at position X, all of the circuits, whether transmission circuits through the repeater or controlling circuits leading to the keys K_1 , K_2 and K_3 , passed over the back contacts of the switching relays 1 to 5, inclusive. It will also be observed that for each of these circuits an alternative path extended from the front contacts of these switching relays to the corresponding apparatus at position Y. The connections to position Y are therefore all opened so that the operator at that position is unable to obtain control of the repeater by inserting the plugs P_1' and P_2' in line jacks and the operator is further unable to interfere with the connection established at position X by manipulating the keys K_1' , K_2' or K_3' .
- If, with the apparatus in its normal condition, the operator at position Y should desire to establish a connection between two

toll lines by inserting plugs P_1' and P_2' in the jacks of the desired lines, a circuit would be completed from the grounded sleeve contacts of the incoming line jack, 5 sleeve contacts of twin plug P_1' through the winding of relay 10 and over the back right hand contacts of relays 9 and 8 to battery. A circuit would also be completed from the grounded sleeve contacts of the 10 outgoing line over the sleeve contacts of the plug P_2' through the winding of relay 11 and over the right hand back contacts of relays 9 and 8 to battery. Relay 10 upon being energized at its left hand contact 15 connects battery from the windings of relays 8 and 9 so that the operator at position X is unable to cause the energization of these relays by attempting to set up a connection. At its right hand front contact 20 relay 10 completes a circuit from ground through the resistance 12 and through the winding of relay 13 to battery. Relay 11 at its right hand front contact completes a circuit from ground through resistance 26 25 and through the winding of relay 27 to battery. Relays 13 and 27 upon being energized connect ground at their lower contacts to the point 28 so that a circuit previously described is completed for the relay 19. Relay 11 at its left hand front contact completes a circuit from battery through the busy lamp 6 at position X to ground thereby causing the lamp to glow to indicate to the operator at position X that the repeater 30 is engaged. A circuit is also completed over the left hand front contact of relay 11 from battery through the windings of relays 1 to 5 inclusive in parallel and thence to ground so that the five switching relays are 35 energized and shift the connections of the various transmission and controlling circuits leading from the repeater of Fig. 2 whereby said circuits are extended to the apparatus at position Y instead of position X. 40

The circuit of the toll cord with the repeater disconnected may now be traced from the left hand tip and ring contacts of the twin plug P_1' over conductors L_1' , left hand front contacts of relay 2, conductors L , back contacts of relay 21, conductors C , right hand front contact of relay 3, conductors C_1' , normal right hand and left hand contacts of the splitting key K_2' over conductors C_2' , left hand front contacts of relay 3, conductors C' , back contacts of relay 23, conductors L' , right hand front contacts of relay 4 and conductors L_2' to the right hand tip and ring contacts of twin plug P_2' . 45

The operator may include the repeater in the cord circuit by actuating the repeater control key K_3' thereby completing a circuit from battery through the winding of filament control relay 29 over conductors 50 and 31', right hand make contacts of control key K_3' over conductor 32', inner front contact of relay 5, conductors 33 and 14 to point 28 and thence to ground over the lower front contacts of relays 13 and 27. Relay 29 completes the filament circuit of the amplifiers A and A' thereby rendering the tubes operative. A circuit is also completed for relays 44, 21 and 23 from grounded point 28 over conductor 34, left hand front contact of relay 1, over conductors 35' and 36', lower normal right hand and left hand contacts of splitting key K_2' , right hand normal contact of listening key K_1' over conductor 37', inner right hand front contact of relay 1 over conductor 38, upper front contacts of relays 13 and 27, conductors 39 and 40', left hand make contact of key K_3' , conductor 41', left hand front contact of relay 5, conductors 42 and 43, winding of relay 44, back contact of relay 45, conductor 46 and through the windings of relays 21 and 23 in parallel to battery. Relay 44 removes short circuits from the input windings of the repeater and connects the repeater to the input bridges 49 and 50 in a manner already described. The operation of relays 21 and 23 connects the repeater to the incoming and outgoing transmission circuits so that transmission between the two toll lines may take place through the repeater. 55

Transmission from the incoming line will pass over conductors L_1' , left hand front contacts to relay 2, conductors L , front contacts of relay 21 through the amplifier A, output circuit 53 and thence in parallel to the outgoing line and the balancing artificial line. The path to the outgoing line extends over the front contacts of relay 23, conductors L' , right hand front contacts of relay 4 and over the conductors L_2' . The path to the artificial line extends over conductors N' , left hand front contacts of relay 4 and over conductors N_2' . In a similar manner, transmission from the outgoing line passes over conductors L_2' , front right hand contacts of relay 4, conductors L' , front contacts of relay 23 through the amplifier A', output circuit 54 and thence in parallel to the incoming line and its corresponding balancing artificial line. The path to the incoming line extends over the front contacts of relay 21 and over conductors L , left hand front contacts of relay 2 and conductors L_1' . The path to the artificial line extends over conductors N , right hand front contacts of relay 2 and conductors N_1' . 60

If ringing currents should be transmitted over the incoming line, the ringing responsive relay 17 would be actuated to open the circuit to relay 19 thereby causing the energization of relay 20. Relay 20 at its right hand front contact completes a circuit for the relay 45 from grounded point 28 over conductor 34, left hand front contact of re- 65

lay 1 conductors 35' and 36', also contacts of splitting key K_2' , right hand normal contact of listening key K_1' , conductor 37', inner right hand front contact of relay 1, conductor 38, upper contacts of relays 13 and 27, conductors 39 and 40', left hand make contact of key K_3' , conductor 41', left hand front contact of relay 5, conductors 42 and 55, front right hand contact of relay 20 through the winding of relay 45 to battery. Relay 45 opens the circuit of relay 44 and completes a holding circuit for relays 21 and 23 in a manner already described. The deenergization of relay 44 results in short circuiting the input windings of the repeater to prevent the transmission of ringing current to the repeater.

Relay 20 at its right hand front contact completes a circuit for the relay 56 which is locked up over its upper front contact, conductors 57 and 58', left hand normal contact of listening key K_1' , conductors 57' and 35', left hand front contact of relay 1 over conductor 34 to grounded point 28. Relay 56 at its lower front contact completes a circuit from ground over conductor 60, right hand front contact of relay 1 and through the lamp 61' to battery.

The glowing of lamp 61' informs the operator that a ring has been transmitted over one of the lines and the operator thereupon throws the listening key K_1' . This operation results in deenergizing the relay 56 and effacing the lamp 61' since it will be remembered that the locking circuit of the relay 56 passed over the left hand contact of the listening key. The circuit of relay 45 which passed over the right hand contact of the listening key is also opened so that said relay is deenergized and again connects relays 21 and 23 in circuit with the relay 44. The circuit for these relays, however, passes over the right hand contact of the listening key which is now open and consequently relays 21 and 23 as well as relay 44, are deenergized. The repeater is now disconnected from the cord circuit and the operator's set is bridged across the portion of the cord circuit including conductors C and C'. By throwing the splitting key K_2' to the left, the operator may exclude the outgoing line from the connection.

If, with the apparatus in this condition, a ring should be transmitted from the outgoing line, relay 16 would be actuated to again open the circuit of relay 19 and cause the energization of relay 20. Relay 45 is not now energized due to the energization of relay 20 as its circuit is opened both at the right hand contact of the listening key and the lower left hand contact of the splitting key. Relay 56 is energized, however, and a locking circuit for said relay is provided over its upper front contact, conductors 57, 58' and 62', lower left hand make

contact of splitting key K_2' , lower right hand normal contact of said key, conductors 36' and 35', left hand front contact of relay 1 and over conductor 34 to grounded point 28. Relay 56 at its lower front contact again completes the circuit of the lamp 61' to indicate to the operator that a ring has been transmitted over the outgoing line. The operator by throwing the splitting key to the right may connect her set with the outgoing line to the exclusion of the incoming line, at the same time momentarily opening the locking circuit of the relay 56 so that said relay is resorted and effaces the lamp 61'.

The operator by restoring the splitting key and listening key to normal again completes the circuit of relays 44, 21 and 23 so that the line may be again connected through the repeater. The connection may be taken down by withdrawing the plugs P_1' and P_2' and restoring the repeater control key K_3' . Withdrawing the plugs results in the deenergization of relays 10 and 11 so that the busy lamp 6 is effaced and the switching relays 1 to 5 are restored to normal. The deenergization of relays 10 and 11 results in opening the circuits of relays 13 and 27 which upon being restored to normal disconnect ground from point 28 so that relays 19, 21, 23, 29 and 44 are deenergized. The apparatus is now restored to its original condition and is ready to be used by the operators at either position X or position Y.

In the connection heretofore described as having been established at position Y, it will be noted that all of the circuits leading from the repeater, whether transmission circuits or controlling circuits, were extended over the front contacts of the switching relays 1 to 5, inclusive, to the apparatus at position Y and were wholly disconnected from the apparatus at position X. Consequently the operator at the latter position was unable to obtain control of the repeater or in any manner interfere with the connection established by the operator at position Y.

By means of the arrangement above described, a simple and efficient means is provided whereby the same repeater may be used in establishing connections at different operators' positions thereby eliminating certain of the apparatus which would otherwise be required with a consequent reduction in the expense involved.

It will also be observed that the general principles herein disclosed may be embodied in many other organizations widely different from that illustrated without departing from the spirit of the invention as defined in the following claims.

What is claimed is:

1. In a signaling system, a repeater, a plurality of lines, manual switching appa-

ratus at one operator's position for associating said repeater with any one of said lines, a second manual switching apparatus at another operator's position for associating said repeater with one of a plurality of lines, and means for placing said repeater under the control of either switching apparatus.

2. In a signaling system, a repeater, a plurality of lines, manual switching apparatus at one operator's position for associating said repeater with any one of said lines, a second manual switching apparatus at another operator's position for associating said repeater with one of a plurality of lines, and means for placing said repeater exclusively under the control of either switching apparatus.

3. In a signaling system, a repeater, a plurality of lines, manual switching apparatus at one operator's position for associating said repeater with any one of said lines, a second manual switching apparatus at another operator's position for associating said repeater with one of a plurality of lines, and means whereby when said repeater is associated with a line by one switching apparatus it is rendered independent of the other switching apparatus.

4. In a signaling system, a repeater, a plurality of lines, manual switching apparatus at one operator's position for associating said repeater with any one of said lines, a second manual switching apparatus at another operator's position for associating said repeater with one of a plurality of lines, and means whereby when said repeater is associated with a line by one switching apparatus it is disconnected from the other switching apparatus.

5. In a signaling system, a repeater and circuits therefor, a plurality of lines, manual switching apparatus at one operator's position for associating said repeater with any of said lines, a second manual switching apparatus at another operator's position for associating said repeater with any one of a plurality of lines, repeater circuit controlling means associated with each switching apparatus, and means for placing said repeater under the control of either controlling means.

6. In a signaling system, a repeater and circuits therefor, a plurality of lines, manual switching apparatus at one operator's position for associating said repeater with any of said lines, a second manual switching apparatus at another operator's position for associating said repeater with any one of a plurality of lines, repeater circuit controlling means associated with each switching apparatus and means for placing said repeater exclusively under the control of either controlling means.

7. In a signaling system, a repeater and circuits therefor, a plurality of lines, manual

switching apparatus at one operator's position for associating said repeater with any of said lines, a second manual switching apparatus at another operator's position for associating said repeater with any one of a plurality of lines, repeater circuit controlling means associated with each switching apparatus and means whereby when said repeater is associated with a line by one switching apparatus it is rendered independent of the controlling means associated with the other switching apparatus.

8. In a signaling system, a repeater and circuits therefor, a plurality of lines, manual switching apparatus at one operator's position for associating said repeater with any of said lines, a second manual switching apparatus at another operator's position for associating said repeater with any one of a plurality of lines, repeater circuit controlling means associated with each switching apparatus and means whereby when said repeater is associated with a line by one switching apparatus it is disconnected from the controlling means associated with the other switching apparatus.

9. In a signaling system, an amplifying repeater and associated circuits, a plurality of switchboard positions, through which connections with said repeater may be established, and means for associating said repeater with any one of said switchboard positions.

10. In a signaling system, an amplifying repeater and associated circuits, a plurality of switchboard positions, through which connections with said repeater may be established, and means whereby when a connection is established to said repeater through one of said switchboard positions said repeater is rendered independent of other switchboard positions.

11. In a signaling system, an amplifying repeater apparatus, a plurality of switchboard positions at the same exchange, repeater connections extending from said repeater apparatus, and means to extend said connections exclusively to any one of said switchboard positions.

12. In a signaling system, an amplifying repeater apparatus, a plurality of switchboard positions, repeater connections extending from said repeater apparatus, and means whereby an operator at one switchboard position can control the extension of said connections to said position to the exclusion of other positions.

13. In a signaling system, a repeater, a plurality of switchboard positions, means to associate said repeater with any one of said switchboard positions and means whereby when the repeater is operatively associated with one switchboard position, a busy signal will be given at another position.

14. In a signaling system, a plurality of

switchboard positions, switching means thereat, a repeater adapted to be connected to any one of said switchboard positions, means whereby when the switching means at 5 one position is actuated the repeater will be associated with that position exclusively and a busy signal will be given.

15. In a signaling system, a plurality of switchboard positions, lines terminating at 10 said positions, a repeater, switching means at each position whereby said repeater may be associated with any of the lines at that position, controlling keys at each position for controlling the functioning of the repeater, and means whereby when the switching means at one position is actuated to associate the repeater with a line at that position the repeater will be rendered independent 15 of the controlling key at another position.

20. 16. In a signaling system, a plurality of switchboard positions, lines terminating at said position, a repeater, switching means at each position whereby said repeater may be associated with any of the lines at that 25 position, controlling keys at each position for controlling the functioning of the re-

peater, and means whereby when the switching means at one position is actuated to associate the repeater with a line at that position the repeater will be rendered independent 30 of the switching means and controlling key at another position.

17. In a signaling system, a plurality of switchboard positions, lines terminating at 35 said positions, a repeater, switching means at each position whereby said repeater may be associated with any of the lines at that position, controlling keys at each position for controlling the functioning of the repeater, busy signals at each position, and 40 means whereby when the switching means at one position is actuated to associate the repeater with a line at that position the repeater will be rendered independent of the switching means and controlling key at another position and a busy signal will be actuated. 45

In testimony whereof, I have signed my name to this specification this 15th day of May, 1919.

OLIVER B. JACOBS.
